[57] CLAIM

The ornamental design for a box, substantially as shown.

DESCRIPTION

FIG. 1 is an isometric view of a box showing our new design in a partially open position;

FIG. 2 is a top plan view in a closed position;

FIG. 3 is a bottom plan view thereof;

FIG. 4 is a side elevational view;

FIG. 5 is a side elevational view showing the side opposite that seen in FIG. 4;

FIG. 6 is a front elevational view;

FIG. 7 is a rear elevational view;

FIG. 8 is a sectional view taken on the line 8—8 of FIG. 2; and

FIG. 9 is a sectional view taken on the line 9—9 of FIG. 5.
